Attorney.

UNITED STATES PATENT OFFICE

2,578,190

FLUORESCENT LAMP HOUSING FOR
CORNER MOUNTING

Albert Kurtzon, Highland Park, Ill.

Application August 30, 1946, Serial No. 693,920

2 Claims. (Cl. 240—4)

1

The invention relates to lamp housings having means for mounting a source of light therein; but more particularly to a housing of this kind which is arranged and adapted to hold a fluorescent tube in shielded and protected position, and to distribute the light therefrom over a counter of a kitchen cabinet or the like; and has for its objects the provision of a housing of this kind which will be simple of construction, economical to manufacture and highly efficient in use.

Other objects will appear hereinafter.

The invention consists of the combinations and arrangements of parts hereinafter described and claimed.

The invention will be best understood by reference to the accompanying drawings forming a part of this specification, and in which

Figure 1 is a perspective view of a fluorescent lamp housing embodying the invention arranged for use over a kitchen counter by being attached to the bottom of a cabinet overhanging said counter;

Figure 2 is a direct front view of a closure for the housing having a pane of glass mounted therein;

Figure 3 is a top plan view;

Figure 4 is a section taken on line 4—4 of Figure 2; and

Figure 5 is a section taken on line 5—5 of Figure 3.

The embodiment of the invention illustrated in the drawings comprises a long narrow housing 10 of triangular cross section, having a top body panel 11 formed integrally with a wall panel 12 and arranged at substantially right angles to each other. Both panels 11 and 12 are provided with suitably placed bayonet slots 13 of a conventional type, and which afford means for either supporting or suspending the housing 10 from suitably placed headed screws or nails when desired or necessity may require. The housing 10 is closed at its ends by suitably flanged triangular shaped panels 14 spot welded to the top body panel 11 and the wall panel 12.

An integral right angle partition 15 is arranged within the housing 10 adjacent the juncture of the panels 11 and 12 extending from contact with an end 14 to a point adjacent the other end and comprises a vertical panel 16 having a mounting flange 18, and a horizontal panel 17 provided with a similar mounting flange 19 arranged and adapted to lie against the body panel 11 and the wall panel 12. The partition 15 is attached by suitable screws (not shown) permitting its ready attachment or removal. The panel

2

17 of the partition 15 is provided with rectangular openings 20 adjacent each end through which lamp brackets 21 protrude, the bases 22 thereof being attached by suitable screws 23, as best shown in Figure 3, the lamp brackets 21 being cooperatively arranged for supporting a fluorescent tube lamp 24 in operative position, as best shown in Figure 3. The arrangement of the partition 15 with its panels 16 and 17 relative to the junctures of the panels 11 and 12 form a passageway 25 in and through which the wires to the lamp brackets may be concealed and properly protected.

An instrument panel 26 of rectangular shape 15 and which is adapted to close a part of the front of the housing 10 is provided with an inwardly projecting triangular shaped flange 28 which, when in position at the end of the partition 15, divides the interior of the housing into a lamp chamber 30, a passageway 25, and an instrument chamber 31. The flange 28 is provided with a hole 32 carrying an insulation bushing 33 held by the locknut 34, thereby forming a protected passageway for the necessary wires from the instrument compartment 31 into the passageway 25 and to the lamp brackets 21. The instrument panel 26 is provided with suitable openings therethrough from which project the faces of the push switch 35 and the service outlet 36. A fluorescent ballast 37 is mounted on the inner side of the flange 28, wholly within the instrument chamber 31.

The adjacent end 14 of the housing 10 carries an insulation bushing 38 which is held in place 35 in the usual manner and through which a suitable electric cord 39 from a source of electricity is adaptedly connected by suitable wiring to the lamp brackets 21 through the fluorescent ballast 37 and the switch 35, and to the service outlet 36.

The instrument panel 26 is provided at its upper edge with an inturned flange 40 which is attached to panel 11 by suitable screw 41. The lower part of the panel 26 is connected by suitable screws 42 to an inwardly projecting flange 43 which extends the full length of the panel 12.

The lamp chamber 30 is closed at its front by a door 44 hingedly connected to the body panel 11 by a piano hinge 45 welded thereto, and when in closed position, as shown in Figure 3, is fastened by suitable screws 46 to the flange 43 forming a part of the panel 12. The door 44 is provided with an opening 47 which is closed by a pane 48 of translucent glass releasably held in place by conventional means for such purposes.

To assemble the lamp for use the partition assembly, comprising the instrument panel 26 formed integrally with the triangular shaped partition 31, is first equipped with the necessary instruments, such as switch 35, electrical outlet 36, and fluorescent ballast 37, and the lamp brackets 21 secured to the panel 18 of the angular partition 15. Suitable wiring is then connected from the switch through the fluorescent ballast 37 to the lamp brackets 21. Lastly the instruments are connected to cord 39 which passes through the bushing 38 (shown in Figure 2) and the whole assembly which comprises the equipped instrument panel 26 and the triangular partition 31 fastened into place within the housing, as will be readily understood.

The specific form and arrangement of parts disclosed is a simple and effective one for the purpose.

While I have illustrated and described a practical embodiment of the invention, this is capable of variations and modifications in the combinations and arrangements of parts without departing from the reality of the invention; I, therefore, do not wish to be limited to the precise details set forth, but desire to avail myself of such changes and alterations as may fall within the spirit and scope of the appended claims.

I claim:

1. A fluorescent cabinet lamp housing having a vertical wall panel and a horizontal wall panel arranged at right angles to each other; triangular end panels secured to both ends of said vertical wall panel and said horizontal wall panel; a plurality of closures arranged at an angle of 45° to the forward edge of said horizontal panel, and to the bottom edge of said vertical panel; a partition arranged intermediate said triangular end panels and connected at its outer edge to one of said closures; a lamp compartment having a closure provided with a transparent window; a lamp supporting partition mounted in said lamp compartment having a vertical front panel secured to said horizontal housing panel at a point adjacent said vertical wall housing panel and a horizontal bracket supporting panel attached at its rearward edge to said vertical

housing panel at a point adjacent its upper edge, there being suitable openings in said bracket supporting panel through which lamp supporting brackets protrude.

2. A fluorescent cabinet lamp comprising an elongated housing having a top and a rear panel at right angles; triangular end walls; closures arranged at 45° angle to said top and rear panels; a vertical partition arranged intermediate said triangular end walls; a longitudinal right angle partition arranged within a light compartment at the upper rearward portion thereof; a horizontal panel portion of said right angle partition carrying lamp brackets in spaced relation; there being suitable openings in said horizontal panel through which portions of said lamp brackets extend downwardly.

ALBERT KURTZON.
